AUTOMATIC CARRIAGE-RETURN MECHANISM FOR TYPEWRITERS

Frederic W. Le Porin, Brooklyn, N. Y., assignor to William T. Andrews, Old Greenwich, Conn.

Application July 27, 1940, Serial No. 347,905

10 Claims. (Cl. 197—66)

This invention relates to automatic return mechanism for carriages of typewriters, and provides improvements therein.

The automatic return operation is usually effected through a key-lever, and the cut-off of the motor mechanism which pulls the carriage on its return movement, is usually effected by a means cooperating with a margin-stop on the typewriter. Inasmuch as there is a considerable variation in the construction of different makes and models of typewriters, great variety is required in the part of the cut-off mechanism which cooperates with the margin-stops of different makes and models of typewriters. It is obvious that there would be great advantages and improvement in a return mechanism for carriages of typewriters, inclusive of the cut-off mechanism, which could be applied without substantial variation to many different makes and models of typewriters.

Such a return mechanism for carriages of typewriters is attained by the present invention; the return mechanism for carriages of typewriters has a motor cut-off mechanism, which can be applied without substantial variation to many different makes and models of typewriters. The carriage return mechanism is wholly self-contained and complete requiring no alteration or attachments to the typewriter other than a driving or pulling connection between the return mechanism and the typewriter. Thereby one type or form of return mechanism may serve for any and all of the ordinary makes of typewriters.

The invention provides an improved return mechanism for carriages of typewriters having the character of general or universal applicability to typewriters as aforesaid, which may be readily set or adjusted to effect the cut-off and stopping of the carriage at virtually any desired position in the return movement of the typewriter.

The invention further provides an improved return mechanism for typewriter carriages by which the carriage on its return movement may be brought against the margin stop mildly, with little shock. The invention further attains a mild stopping of the carriage against the margin stop under different conditions of carriage travel. The return movements of carriages vary, and in such return movements the momentums vary, the momentum of a carriage on a long return being greater than its momentum on a short return. By the present invention this variable is automatically compensated, and a mild stopping of the carriage against its stop is attained irrespective of the aforesaid variable. This is particularly important

with typewriters equipped with long, or extra-length carriages.

The carriage return mechanism according to the invention can be applied to typewriters with virtually no alterations or additions to the mechanism of the typewriter and with no alteration of the normal functioning of the typewriter, the return mechanism functioning collaterally or alternatively with the manual return operation.

The invention further provides a mechanism which is very simple, and economical to build and to install, and on which the servicing should be minimum after installation.

The novelty of the present invention resides principally in that part of the combination of elements constituting an automatic return mechanism for typewriter carriages which functions to effect the cut-off or stopping of the motor after the carriage return-movement has been initiated. The motor-mechanism and the mechanism by which the motor is put into operation to return the carriage may have various forms, or embodiments. The carriage return mechanism disclosed and claimed in the patent of Frederic W. Le Porin, No. 2,214,906, has many desirable features, and parts of that combination are incorporated in the illustrated embodiment of the present invention, wherein:

Fig. 1 is a view essentially in elevation of a typewriter and a carriage-return mechanism associated therewith. The stops and stop-rail appearing at the top of the figure would normally appear in plan but have been shown in elevation for simplicity and clearness.

Fig. 2 is a view of the carriage-return mechanism in side elevation.

Fig. 3 is a view of the parts shown in Fig. 2, in top plan.

Fig. 4 is a view in side elevation, viewing the parts from the opposite direction to the viewpoint of Fig. 3, looking at them from a plane running in front of the motor, Fig. 2. In this view the rocking beam 101 and the cam 107 have been shown at the front of the synchronously movable part 80, these parts in the other views being located on the opposite side of the synchronously movable part 80. This has been done to facilitate the comprehension of the invention from the drawings.

Fig. 5 is a detail view illustrating the controller bar 55, and its relation to the switch and clutch arms.

Fig. 6 is a side elevation of a modified form of the detent.

Referring to said drawings, numeral 10 design-

nates a motor having suitable connections to a typewriter carriage C and through which connections the motor operates to return the carriage to a line-beginning position. The putting into operation of the motor to effect the return movement of the carriage is effected by any suitable means. The automatic cutting out of the motor and the stopping of the carriage on its return movement is effected by cutting-off means having novel and advantageous features hereinafter described.

The motor 10 and the means connecting it to the typewriter carriage, and also the means for putting the motor into operation to effect the return movement of the carriage, may advantageously be similar to those illustrated and described in the patent of Frederic W. Le Porin, No. 2,214,906. A brief description of the aforesaid parts of the carriage return mechanism will be first given. A description in greater detail is found in said Le Porin patent.

The motor 10 has a shaft 12, and a worm 14 thereon which meshes with a worm gear 16 on a counter shaft 18 having a suitable connection to the typewriter carriage C. As here shown the counter shaft 18 may drive a drum 20 to which is connected one end of a tape 22 the other end of which is attached to the typewriter carriage C. The tape 22, as here shown, may be attached to the platen shift-lever L on the carriage C, so that line spacing may be effected simultaneously with the carriage return. The tape 22, between the drum 20 and the shift lever L, may be guided in any suitable and appropriate manner. A bracket B having guide rollers thereon is illustrated. The counter shaft 18 is advantageously connected to the drum 20 through a universal joint 24.

A clutch 30 is advantageously interposed between the motor 10 and the counter-shaft 18. In the construction illustrated, the clutch comprises a toothed disk 32 fastened on the counter-shaft 18 and a toothed disk 34 carried by the worm gear 16. The worm gear 16 is loose on the counter-shaft 18, and the counter-shaft has a limited amount of longitudinal movement so that the toothed disks 32 and 34 may be brought into and out of engagement. The shifting of the counter-shaft 18 to effect engagement and disengagement of the clutch 30, may be effected by a forked lever 36 which engages a collar 38 fast on said counter-shaft. The forked arm 36, may, as here shown, be acted on by a spring 39 in a direction to engage the clutch.

The motor 10, as here shown, is an electric motor, and it may be started and stopped through a switch 40. The switch 40 has an arm 41 by which it is turned to open and closed position. As shown, a spring 44 acts on the arm 40 in a direction to open the switch.

The means for putting the motor into operation to effect return movement of the carriage may, as here shown, comprise key-levers 50 and 51. The key-lever 50 may be designated as an automatic full-return key-lever, and the key-lever 51 as an automatic limited-return key-lever. These key-levers 50 and 51 operate upon the forked clutch-lever 36 and the switch arm 41 through a controller, here shown as a bar 55 having a limited longitudinal movement, and biased or constrained in one direction by a spring 57. Under the action of the spring 57 the controller bar 55 acts on the clutch lever 36, through a pin 58, in a direction to disengage the clutch. The controller bar 55 also acts on the switch arm 41 through a notched

portion 59. The switch arm 41 is normally acted on by its spring 44 in the direction to open the switch. The switch 40 is closed by the controller bar 55 when it is moved against the action of its spring 57 and contacts with switch arm 41 and moves it to switch closing position. At the same time the pin 58 on the controller bar 55 moves away from the clutch lever 36 and allows the clutch lever to be turned by the spring 39 to move the clutch parts 32 and 34 into engagement.

A detent 65 is provided which coacts with an arm 66 on the controller bar 55. When the controller bar is pushed against the tension of its spring 57 (towards the left in Figs. 2 and 3), and the detent 65 is free to rise, the detent engages the arm 66 and when so engaged serves to hold the controller bar in clutch and switch-closing position until the detent 65 is actuated to release the controller bar as hereinafter described.

The motor is put into operation to effect return movement of the carriage by pressing either the automatic full-return key-lever 50 or the automatic limited-return key-lever 51. When the automatic full-return key-lever 50 is depressed it acts through a pawl 70 pivoted on its lower end, against a pin 71 on the controller bar 55 to move the said controller bar 55 against the tension of the spring 57 to a position where the detent 65 can rise to engage the arm 66 on the controller bar and hold the controller bar in such actuated position until the detent is released. The actuation of the controller bar 55 by the automatic full-return key-lever 50 moves the switch arm 41, against the action of its spring 44, to close the circuit to the motor 10 through the switch 40 and start the motor in operation. At the same time the pin 58 on controller bar 55 is moved away from the forked lever 36, allowing its spring 39 to act on the forked lever to move the counter-shaft 18 having the clutch disk 32 thereon, into engagement with the clutch part 34. When the clutch parts are in engagement, the rotation of the shaft 12 is transmitted to the counter-shaft 18 and to the drum 20. As the drum 20 rotates, the tape 22 winds thereon. The pull of the winding-on tape moves the carriage to the right, to a position where line writing is to begin. With the tape 22 attached to the spacing lever L the platen roller on the carriage is moved forward in a manner well understood, so that the typing begins one or more spaces below the previously completed line of typewriting.

When the automatic limited-return key lever 51 is depressed it acts against the pin 73 on the controller bar 55 to move said controller bar against the tension of its spring 57 (toward the left, Figs. 2 and 3) to close the clutch and switch, just as when the key lever 50 is depressed, except when the key lever 51 is depressed the detent 65 does not act to retain the controller bar 55 in its key actuated position. The key lever 51 has an arched projection 75 thereon which comes into contact with the detent 65 when the key lever 51 is depressed, and thereby holds the detent 65 depressed so that it cannot engage the arm 66 on the controller bar 55, and the controller bar is free to return under the action of the spring 57 when the key lever 51 is released.

When the controller bar 55 is engaged by the detent 65 the motor continues to return the carriage until the controller bar 55 is released by the detent 65. The point of release of the detent 65 corresponds with the position of the typewriter carriage on its return movement at which line writing is to begin. The actual release of

the controller bar 55 by the detent 65 is preferably effected slightly (5 to 10 spaces for example) before the margin stop X strikes the carriage stop Y, so that the stops X and Y may come together with a mild impact under the influence of the carriage momentum and the counter action of the usual carriage feed spring (not shown).

Typewriters differ quite considerably as to makes and models. Heretofore the means for cutting off the action of the carriage-return motor have been associated with a margin stop or similar part of the carriage on the typewriter, and this requires considerable differences in the cutting off mechanism for different types and models of typewriters. According to this invention, the cutting off means is off of the typewriter carriage, and has the same construction for many makes and models of typewriters.

According to the present invention the cutting-off means comprises a part 80, off of the typewriter carriage, which moves in synchronism with the typewriter carriage, and which is constructed and arranged to coact with the motor cutting-off means (switch, or switch and clutch) to cut off the motor at a position of the synchronously movable part 80 corresponding to a predetermined position of the carriage C at which line-writing is to begin, or proximate thereto.

Suitable means are provided for bringing about movement of the part 80 in synchronism with the carriage. In the illustrated embodiment this may be effected by a gearing connected with the drum 20. As here shown, the drum 20 may carry a notched disk 82 which engages a star-wheel 83. The star-wheel 83 advantageously drives the synchronously movable part 80 through a reduction gearing comprising the gears 84, 85, 86. The synchronously movable part 80 is advantageously a disk which is provided with gear teeth 87 which mesh with the gear 86, and is carried on a movable part 89 by which the teeth 87 thereon may be moved into and out of mesh with the gear 86. The action of the reduction gearing is advantageously such that the synchronously movable part 80 has somewhat less than 360° of angular movement for such number of rotations of the drum 20 as may result from its connection through the tape 22 to the carriage C, throughout the full movement of the carriage. The length of travel of the ordinary typewriter carriage is 9 inches and long carriages sometimes have a travel of 30 inches or more.

The synchronously movable part 80, as heretofore mentioned, coacts with the detent 65. To this end the synchronously movable part 80 may be provided with a stud or projection 95, and the detent 65 may be provided with a coacting part 96 which is located in the path of movement of the said projection 95.

Coacting part 96 may be a small projection on the detent 65, as shown in Fig. 6. In the other views illustrated the said coacting part 96 is formed on a separate part 98 connected to the detent 65 and having an advancing and retarding movement with relation to the stud 95, and forming part of the mechanism whereby the cutting-off of the motor is automatically varied to compensate for differences of carriage momentum due to differences of distance of carriage return. The part 98 is a floating part having a pin and slot connection with the detent 65, as indicated at 99, and also having a pivotal connection to a rocking beam 101, as indicated at 102. The rocking beam 101 is pivoted, as indi-

cated at 103, and has an arm 105 which bears on a cam 107 fixed to or turning with the synchronously movable part 80. The arm 105 of the rocking beam 101 is normally constrained to bear on the cam 107 by a spring 109. The rocking beam also has thereon an arcuate portion 111 which coacts with a clamp 113 in such manner that the arm 105 of the rocking beam 101 is held in an elevated position, and unable, during a certain part of the operation of the device, to follow the cam 107. While the rocking beam 101 is held by the clamp 113, as aforesaid, the floating part 98 carrying the projection 96 which coacts with the stud 95 on the synchronously movable part 80, is held in a certain position of advance with relation to the said stud 95, as will be hereinafter more fully explained. Clamping part 113, as here shown, has the form of an arm 115 movable on a pivot 116, and also carries the roller 117 or equivalent part arranged to coact with the arcuate portion 111 of the rocking beam 101. The pivoted arm 115 has a heel 119 located in the path of movement of a stud 120 carried by the controller bar 55. When the controller bar 55 is in clutch and switch closing position (toward the left in Fig. 2), the stud 120 thereon moves away from the heel 119, and allows the spring 122, acting on said clamping arm 115, to move said arm 115 on its pivot and bring it into clamping relation with the arcuate portion 111 of the rocking beam 101. When the controller bar 55 is in switch and clutch opening position the stud 120 thereon acts against the heel 119 so as to turn the clamping arm 115 to bring the roller 117 thereon to a position on or slightly beyond the arc of said arcuate portion 111. This position of the clamping arm 115 is illustrated in Fig. 2. By reason of the relationship of the pivot 103 of the rocking beam 101 and the pivot 116 of the arm 115, the roller 117 on arm 115 moves toward the arcuate portion 111 when the stud 120 on controller bar 55 is moved away from the heel 119, and the spring 122 is free to turn arm 115 on pivot 116. As long as stud 120 on controller bar 55 acts on the heel 119 of clamping arm 115, the rocking beam 101 may move up or down free of the restraint of the clamping arm 115, but when the stud 120 moves away from the heel, and the spring 122 acts to turn said clamping arm, the roller 117 on said clamping arm 115 is brought into clamping or binding relationship with the arcuate portion 111 of said rocking beam 101 and holds the said rocking beam against the action of its spring 109, and thereby disengages arm 105 to follow the cam 107, as previously stated.

In the position of the typewriter C at which line writing is to begin (see Fig. 1), the synchronously movable part 80 is in the position where it has coacted with the detent 65 and associated mechanism to cut off the motor 10.

In the form of embodiment shown in the drawings, the stud 95 on the synchronously movable part 80 stands a short distance away from the projection 96 (corresponding to a few letter spaces), and the detent 65 is held depressed out of position to engage the arm 66 on the controller bar 55, the said controller bar 55 being in clutch and switch opening position (position shown in Fig. 2). In this position line spacing without carriage return may be effected by depressing key 50, the operation of key 50 moving controller bars 55 to switch and clutch closing position (toward the left, Fig. 2), detent 65 momentarily rising to engage the arm 66 on the

controller bar, and said detent being almost immediately disengaged by the movement of the stud 95 on the synchronously movable part against the projection 96 to depress the detent 65 and disengage it from the arm 66, so that spring 67 acting on the controller bar can move it to switch and clutch opening position (position shown in Fig. 2). Alternatively, the stud 95 on the synchronously movable part 80 could rest against or on the projection 96 in the line-writing beginning position of the carriage, in which position line spacing without carriage return can be effected by depression and release of either lever 50 or 51.

When the keys attached to the type bars (not shown) are manipulated and typing is done, the carriage C, under the influence of the usual feed spring and escapement (not shown) moves to the left. As the carriage C moves to the left, the synchronously movable part 80 is also moved through the connections between the carriage C and the said synchronously movable part 80, these connections in the illustrated embodiment being the tape 22, drum 20, notched disk 82, star-wheel 83, gears 84, 85, 86 and gear teeth 87. As the movement of the carriage in typing continues, the stud 95 on the synchronously movable part 80 moves away from the projection 96 on or connected with the detent 65, the distance of movement of said stud 95 away from said projection 96 being proportional to the movement of the carriage C.

When the end of a line of typing is reached and it is desired to return the carriage C to line-beginning position, the automatic full-return key lever 50 is struck. The depression of the key lever 50, through the coaction of pawl 70 and pin 71, moves the controller bar 55 to a position where the detent 65 can rise and engage the arm 66 on the said controller bar 55. This movement of the controller bar 55, as heretofore described, closes the switch 40 and the clutch 30, whereupon the motor 10 is put into operation, driving the countershaft 18 and the drum 20, the rotation of the drum winding the tape 22 thereon and pulling the carriage toward the line-beginning position (toward the right, Fig. 1). During the return movement of the carriage, the synchronously movable part 80 of the motor cut-out means, moves synchronously with the carriage (through the means heretofore described), and the stud 95 on said synchronously movable part 80 makes contact with the projection 96 on or connected with the detent 65 at or about the time the carriage C reaches its line-beginning position, which position is usually determined by the margin stop X. When, as here illustrated, the mechanism comprises means for automatically controlling the impact of the carriage against the margin stop under different conditions of carriage momentum, the motor cut-off through the switch and clutch is effected at varying distances of the carriage from the margin stop which determines the line writing beginning position, as has already been described to some extent and as will be more fully described hereinafter.

Contact of the stud 95 with the projection 96 acts to release the controller bar 55 from the detent 65. Even without the means for automatically compensating for varying momentums of the carriage, the action of the stud 95 on synchronously movable part 80 advantageously occurs a few spaces in advance of the contacting of the margin stop X with carriage stop Y. The

momentum of the carriage, after the motor is cut out, can be utilized to continue the movement of the carriage C for a distance corresponding to a few spaces, with the advantage that the shock or impact when the stops X and Y make contact is moderated and may be made very mild.

The action of the means for compensating for the carriage momentum consequent upon differing distances of carriage return, will now be particularly described.

The rotation of the synchronously movable part 80, as previously described, being proportional to the carriage travel, the part 80 will turn through a greater or less angular distance depending on the distance of the carriage-return movement. Thus, for example, with a nine-inch carriage the return of the carriage through the full length of the line will be approximately nine inches. On a 30-inch carriage the carriage return distance from the end of a full line would be approximately 30 inches. Also, with a 30-inch carriage the distance of return from the middle of a full line would be 15 inches, and so on. The momentum acquired by the carriage on the return is different for short return distances than that for long return distances. With greater momentum of the carriage the motor can be cut off with the carriage further from the return margin stop than with lesser momentum, the momentum being relied on to carry the carriage to the margin stop after the motor has ceased to act. The parts comprising the cam 107, rocking beam 101 and floating part 98 act automatically to cut off the action of the motor a greater or less distance of the carriage from the margin stop, depending on the distance from the margin stop that the carriage travels on its return.

As the carriage moves away from the line-beginning position under the action of the carriage spring and the intermittently acting escapement, in the act of typing, the synchronously movable part 80, through the tape 22, drum 20, star-wheels 82, 83 and gears 84, 85, 86, is moved a proportional distance, moving the stud 95 thereon a correspondingly proportional distance from its initial position. The cam 107 moving with the synchronously movable part 80 acts on the arm 105 of the rocking beam 101 elevating it and turning it by an amount corresponding to the contour of the cam. As the rocking beam 101 turns, it moves the floating piece 98, and the projection 96 thereon, in the direction of the return movement of the stud 95. That is, it advances the projection 96 with relation to the initial position of the stud 95. While the carriage is advancing in the act of typing, the controller bar 55 is in a position for the pin 120 thereon to act on the heel 119 of arm 115 to hold the roller on arm 115 out of binding contact with the arcuate portion 111 of said rocking beam 101. At this time, under the action of cam 107, the rocking beam 101 can turn unrestrained by the clamping arm 115. The floating part 98 is connected to the detent 66 through the pin and slot connection 99.

When the carriage-return key 50 is depressed the rocking beam 101 is locked or clamped in the position to which it has been moved by the cam 107. It is held so clamped throughout the return movement of the carriage when the full-return key lever 50 is depressed, and while the rocking beam 101 is held so clamped, the projection 96 on the floating part 98 is held in the position of advance proportional to the movement of the

carriage in typing, to which it has been advanced by the carriage movement. The locking or clamping of the rocking beam 101, just stated, is effected by the movement of the controller bar 55 through the action of said carriage-return key 50. When the controller bar 55 is moved under the action of key lever 50 to close the clutch 32, 34, and motor switch 40, it moves towards the left (Fig. 2), carrying the pin 120 away from the heel 119 of clamping arm 115 and allowing the roller 117 on said clamping arm to move under the action of its spring 109 into binding or clamping relation with the arcuate portion 111 of rocking beam 101. At the same time that the beam 101 is clamped, the motor switch 40 and clutch 32, 34 are closed, starting the return of the carriage. As the carriage approaches the margin stop at the line-beginning position, the stud 95 on the synchronously movable part 80 approaches the projection 96 in a position of greater or less advance, as heretofore explained, with relation to the initial position of stud 95, and consequently the stud 95 strikes the projection 96 before reaching its initial position, thereby opening the motor switch and clutch when the carriage on its return movement is a greater or less distance from the margin stop, depending on the momentum of the carriage. The momentum carries the carriage on its return movement against the margin stop after the motor has been cut off. The opening of the motor switch and clutch, and the cutting off of the motor is effected when the stud 95 strikes the projection 96 depressing the floating part 98, and thereby depressing the detent 66, through the pin and slot connection 99, releasing the arm 66 on the controller bar 55 from the detent. When released, the controller bar 55, under the action of the predominant spring 57, moves the said controller bar to the right (Fig. 2), acting to open the clutch through the action of pin 58 on forked arm 36 and to open the switch through the switch arm 41. By the same movement of the controller bar 55 by which the clutch and motor switch are opened, the pin 120 strikes the heel 119 of the clamping arm 115, and turns said arm 115 to a position where the rocking beam 101 is released and free to turn unhampered by the said clamping means.

The momentum compensating cut-off of the carriage-return motor, effected through the cam 107, rocking beam 101 and floating part 98 has just been described. A cut-off of the carriage-return motor a few letter spaces in advance of the line-beginning position has also been referred to. This may be arranged by connecting the tape 22 to the line-spacing lever L on the typewriter carriage, and setting the stud 95 on the synchronously movable part 80 just out of contact with the projection 96 on or connected to the detent 66 when the margin stop X on the carriage is against the stop Y on the typewriter frame and the line-spacing lever L free. With the parts thus arranged, the apparatus acts to cut out the motor 10 at a position of the carriage somewhat in advance of its line-beginning position, i. e. before stops X and Y can come into contact. The reason for this is that when the drum 20 starts to turn, some of the tape 22 is wound thereon before the pull of the tape starts the return movement of the carriage. When the tape 22 first starts to pull, the line-spacing lever L yields, and a length of tape corresponding to the length of the arc through which the lever L moves at the point of connection to tape 22,

winds on the drum 20 before the carriage starts to move. Synchronously movable part 80, being driven with the drum 20, therefore starts its movement toward the cut-off position before the carriage starts its return movement, and in consequence the synchronously movable part 80 reaches cut-off position (stud 95 contacts with projection 96) in advance of the carriage reaching line-beginning position (stops X and Y contacting) by an amount of carriage travel represented by the aforesaid arc of movement of the line-spacing lever L. This not only softens the impact between the margin stops X and Y, but also permits the normal operation of the controller bar 55 under the action of the full-return key lever 50 even with the carriage in its line-beginning position with the stops X and Y in contact. The movement of the tape 22 through the arc of movement of the line-spacing lever L allows the synchronously movable part 80 to move sufficiently for the stud 95 thereon to contact with the projection 96 and depress the detent to release the controller bar 55 and cut off the motor, and, when the motor is released, to enable the said stud 95 to move sufficiently away from the projection 96 to enable the detent to again rise and lock (momentarily) the controller bar 55 in switch and clutch closing position when the full-return key lever 50 is again depressed. When the full-return key lever 50 is depressed with the carriage in line-beginning position and stops X and Y in contact, it will of course be understood that line spacing is effected without lateral movement of the carriage. Also, under these conditions the motor is not stalled with current on.

The limited-return key lever 51 can be depressed to effect return movement of the carriage. The limited return key lever 51 is ordinarily used to effect short return movements of the carriage. The limited return key lever 51, among other uses, may be used in tabulating, where the typing in any line is usually short, and skillful operators are able to effect a return of the typewriter carriage very close to a position thereof where typing in a column is to begin. The limited return key lever is held depressed for the length of time it is desired the carriage return mechanism to operate; the automatic full-return key lever need only be depressed momentarily, the carriage return mechanism thereafter continuing to operate to return the carriage until the carriage is returned to its line-beginning position (or to the automatically varied cut-off positions heretofore described at length), whereupon the motor is automatically cut out.

In the operation of typewriters, the line-beginning position is often set at different positions of the carriage C. The present invention includes means by which the motor 10 may be cut out at different positions of the carriage C corresponding to different line-beginning positions thereof. Means are provided for changing the position of the synchronously movable part 80 relative to the carriage C, so that said synchronously movable part 80 may be set forward or backward to begin movement in synchronism with the carriage C, at different distances from the initial position of stud 95, corresponding to the distances the carriage is set to travel to reach line-beginning position. Such means may be, as here shown, a key lever 130 on which the synchronously movable part 80 is mounted, which lever 130 may be depressed to disengage the teeth 87 on part 80 from the gear 86, and

thereby allow the synchronously movable part 80, and the stud 95 thereon, when the teeth 87 are so disengaged from the gear 86 to be moved and set at an initial position corresponding to that at which it is desired to stop the carriage on its return movement. Disengagement of the teeth 87 from the gear 86 is conveniently provided for by pivoting the key lever 130, as indicated at 132. A spring 135 may be provided for acting on the key lever 130 in a direction to normally hold the teeth 87 in engagement with the gear 86. In the construction shown synchronously movable part 80 is not mounted directly on the lever 130, but on an arm 137 pivoted at 139 and having a pin and slot connection to the key lever 130, as indicated at 141, 142. The slot 142 allows a short movement of the key lever 130 before movement is imparted to the lever 137, and thereby moderates the force with which the teeth 86, 87 engage and disengage. The position of the teeth 86, 87 in engagement, at the pitch circle may be nicely adjusted by means of an adjustable stop 144 acting on the lever 137. A spring 147 acts on the pivoted arm 137 in a direction to normally press the lever to the position where the teeth 87 on the synchronously movable part 80 engage the teeth 86.

Means are also advantageously provided for automatically bringing the synchronously movable part 80 and the stud 95 thereon to the initial position when the key lever 130 is depressed. These means may comprise a spring 150 attached at one end to the lever 137, as indicated at 152, and at its other end to a stud 155 positioned eccentrically on the synchronously movable part 80. While the teeth 87 on the synchronously movable part 80 are in engagement with gear 86, the spring 150 readily yields to permit movement of the said part 80. If, however, the said part 80 and the stud 95 thereon is in any other position than its initial position (see Fig. 2), when the reset key lever 130 is depressed the teeth 87 on the part 80 are disengaged from gear 86 and the spring 150 will act on the part 80 to bring it to its initial position. That is, the stud 95 on the synchronously movable part 80 is brought to a position adjacent the projection 96 on or connected to the detent 65, the adjacency corresponding to the movement of the synchronously movable part 80 corresponding to the line-spacing movement of the line-spacing lever L to which the tape 22 is connected. That is, with the stud 95 in its initial position adjacent the projection 96, the said stud 95 is movable by an amount to contact with and depress the projection 98 in the amount of movement of the tape 22 which corresponds to the arc of movement of the line spacing lever L in line spacing. As the line-spacing lever L is moved as in line spacing, the stud 95 moves to depress projection 96, and as the line-spacing lever L moves to its initial position when released, the stud 95 on the synchronously movable part 80 through the pull of the tape, moves to its position of adjacency to the projection 96, which is the initial position when the carriage-return mechanism is connected to the carriage through the line-spacing lever L.

With the construction thus described, when it is desired to change the position at which the carriage-return motor is cut out on the return movement of the carriage C, so as to change the line-beginning position of the carriage, this change may be readily and conveniently effected

by moving the carriage C to the new position at which typing is to begin, releasing line-spacing lever L and then depressing the reset key lever 130. When the teeth 87 on the part 80 are disengaged from the gear 86, the spring 150 acts to move the synchronously movable part 80 to a position where the stud 95 thereon is in its initial position with relation to the projection 96. This is the position of adjacency just described, corresponding to the arc of movement of the line-spacing lever to which the tape 22 is connected. The reset lever 130 is then released, whereupon the teeth 87 re-engage the gear 86. The synchronously movable part 80 is now set (or reset) to effect the cut off of the motor 10 at the new line-beginning position. The carriage C may be set at any position corresponding to any desired line-beginning position, and, by resetting the synchronously movable part 80 in the manner heretofore described, the automatic cut-out of the motor 10 and the stopping of the carriage at any new line-beginning position may be effected.

As a result, the stopping conditions are alike for each line-beginning position. That is, the stopping conditions are the same whether the margin stop is set to allow the full extent of movement in the right-hand direction, or whether it is set to allow the carriage to move any less part of its full extent of movement, as one-half, one-third, one-fourth, etc. Also the stopping conditions are the same for these different margin-stop positions, when the distance away from the stopping-position at which the carriage return is initiated is the same. The advance of the motor cut-off is the same when the carriage return is initiated twenty spaces away (for example) from a line-beginning position of the carriage half-way of its full extent of movement as it is when the carriage return is initiated twenty spaces away from a line-beginning position at the full extent of the carriage movement on the frame.

The controller bar 55, with detent 65 and the key levers 50, 51 and 103 are arranged in closely adjacent parallel planes, and provide a compact arrangement, and this compact arrangement is preserved by arranging the synchronously movable part 80 in a plane parallel and adjacent to the plane of the controller bar 55. The arrangement of the star-wheels 82, 83 applies the torque of the counter shaft 18 to the reduction gears and synchronously movable parts at a 90 degree angle and favors said compact arrangement.

Résumé of operation

This résumé is made with reference to the specific embodiment illustrated in the drawings.

The operator determines the position of the carriage C at which the line of typing is to begin, and ordinarily makes use of the scale S on the typewriter carriage. This point may be any number of spaces to the right of the zero point on the scale. The adjustable margin stop X is set at the point on the scale where it is desired that the line of typing is to begin. The carriage C is then moved manually to bring the margin stop X against the carriage stop Y. In this position the operator presses the key on the reset key lever 130. This action disengages the teeth 87 on the synchronously movable part 80 from the gear 86, and, when the synchronously movable part 80 is disengaged, the spring 150 acts on the part 80 to turn it to its initial position, that is, where the stud 95 thereon is in its position of

adjacency to the projection 96, determined by the arc of movement of the line-spacing lever L, to which the tape 22 is connected. The reset lever 130 is then released so that the teeth 87 on the part 80 may re-engage the gear 80. The operator then manipulates the typebar keys to write a line and the carriage C advances to the left in Fig. 1 under the action of the carriage feed spring and the typewriter escapement. The carriage C in moving to the left acts on the drum 20 through the tape 22 in clockwise direction, and the movement of the drum 20 through the action of the star-wheels 82, 83 and reduction gearing 84, 85, 86 turns the synchronously movable part 80 in a direction to carry the stud 95 away from the projection 96 on or connected to the detent 65, and the extent of movement of the stud 95 away from the projection 96 is proportional to the movement of the carriage in line writing, and likewise proportional to the movement apart of the stops X and Y. The drum 20 is normally under a light counter-clockwise tension, which is just sufficient to take the slack out of the tape 22, so that when the typewriter carriage moves to the left the tension of the tape on the shift lever L is not sufficient to move the shift lever.

As the synchronously movable part 80 and the stud 95 thereon is moved away from the projection 96 under the line-writing movement of the carriage (through the tape 22, star-wheels and gears) the cam 107 moves with the said synchronously movable part 80. As the cam 107 turns, as thus stated, it lifts the arm 105 of the rocking beam 101 by an amount corresponding to the angular movement of said part 80 and the contour of the cam 107. During this time the clamping means 113 is held out of binding contact with the arcuate portion 111 by the action of the pin 120 on the controller bar 55 against the heel 119 on the clamping arm 115. The lifting movement of the arm 105 of the rocking beam 101 advances the floating part 98 carrying the projection 96 in the direction of the return movement of the stud 95, that is, forward with relation to the initial position of said stud 95. The floating part 98 is connected to the detent 65 through the pin and slot connection 99.

When the end of the line is reached and the operator desires to return the carriage to line-beginning position, the automatic full-return key lever 50 is depressed and released. The action of the lever 50 is to move the controller bar 55 to a position where the detent 65 engages the arm 66 on the controller bar 55 and holds the controller bar 55 against the action of its predominant spring 57. The movement of the controller bar 55, as just described, carries the pin 120 thereon away from the heel 119 on the clamping arm 115 and allows the roller 117 to move into locking or clamping relation to the arcuate portion 111 on the rocking beam 101, under the action of the spring 122. The clamping or locking action of the arm 115 holds the rocking beam 101 in the position to which it had been moved by the action of the cam 107 on the arm 105. The projection 96 on the floating part 98 is likewise locked in the position to which it had been advanced by the rocking beam 101.

The action of the controller bar 55 when the key lever 50 is depressed, and during the time it is held by the detent 65, is to move the switch lever 41 to close the circuit to the motor 10 through the switch 40 and to release the clutch lever 36 so that its spring 39 turns the clutch lever to move the countershaft 18 longitudinally

and thereby engage the parts 32, 34 of the clutch 30, thus connecting the motor to the drum 20 which carries the tape 22 which is connected to the typewriter C, the said connection in the illustrated embodiment being to the line-spacing lever L which acts to turn the platen one or more spaces, according to the desired distance between the lines of typewriting.

While the controller bar 55 is held by the detent 65 the motor rotates the countershaft 10 and the drum 20 thereof, and the tape 22 winding on the drum 20 exerts a pull on the carriage C in the carriage-return direction. The drum 20 while the motor 10 acts thereon turns in a counter-clockwise direction. The first effect of the pull of the tape 22 is to turn the shift lever L to rotate the platen one or more line spaces, in the usual and well known manner. During the turning movement of the shift lever L the tape 22 winds on the drum 20 a distance corresponding to the length of the arc of movement of the shift lever at the point where the tape 22 is connected thereto. During this time the stud 95 on the synchronously movable part 80 is moving toward the detent 65 a distance in proportion to the length of the tape 22 wound on the drum 20 during the movement of the shift lever L. During this time, also, the carriage C stands still, and the synchronously movable part 80 has a lead or advance over the carriage on its return movement, which, translated into spaces on the scale S, is ordinarily a distance of a few letter spaces.

When the shift lever L reaches the end of its turning movement under the pull of the tape 22, the return movement of the carriage C begins. During the return movement of the carriage, it and the synchronously movable part 80 move in synchronism, with a small lead in favor of the synchronously movable part.

When the stud 95 on the synchronously movable part 80 comes into contact with the projection 96 on or connected with the detent 65, the detent 65 is depressed, disengaging it from the controller bar 55. When so disengaged the controller bar 55 under the influence of its predominant spring 57, moves to the right (Fig. 2), turning the clutch lever 36 to disengage the parts 32, 34 of clutch 30 and to release the arm 41 of the switch 40, so that the spring 44 acting on the switch arm 41 moves the switch to open position and opens the circuit to the motor 10. At this time the return movement of the carriage C has not been completed owing to the lead of the synchronously movable part 80 over the carriage on the return movement, and owing to the momentum compensating advance of the projection 96 carried by the floating part 98 attached to the rocking beam 101, but the carriage C has a momentum which is sufficient to bring the stop X on the carriage against the stop Y on the frame. The compensation effected by the advance of the projection 96 brings about the result that the momentum remaining in the carriage at the time of the motor cut-off, irrespective of the amount of momentum in the carriage at that time, suffers such a loss between the time of the motor cut-off and the time the stops X and Y make contact, that the contact of said stops X and Y is always mild, and substantially or approximately uniform. As previously described, the advance of the projection 96 on the floating part 98 connected to the rocking beam 101 is greater and greater as the distance of the carriage return is greater and greater, as determined by the angular movement of the syn-

synchronously movable part 80 and the contour of the cam 107 which moves with said synchronously movable part 80.

When the controller bar 55 is released from the detent 65 through the action of the stud 95 and projection 96, as described shortly above, the pin 120 thereon is moved against the heel 119 of the clamping arm 115, moving it down to a position where the rocking beam 101 is released, and free to move. When free to move, its spring 109 pulls the arm 105 down into contact with cam 107, and the rocking beam 101 is thereupon free to move under the action of the cam 107 until the clamping means 113 is again brought into clamping relation with the arcuate portion 111 through the action of the controller bar 55 following the actuation of the latter by the key lever 50.

When it is desired to return the carriage a short distance within its full-return movement, the limited-return key lever 51 may be depressed. The return movement of the carriage continues as long as the limited-return key lever 51 is held in its depressed position. In its depressed position the limited-return key lever 51 moves the controller bar 55 to switch and clutch closing position through its contact with the pin 73. The projection 75 on the limited-return key lever 51 prevents the detent 65 from rising to engage the arm 66 on the controller bar 55, and, when the limited-return key lever is released, the controller bar 55 is immediately free to act under the influence of its predominant spring 57 to disengage the clutch 30 and open the switch 40.

When the motor 10 is disconnected through the clutch 40, the carriage C may be manipulated by hand with the same freedom and completeness as without the automatic carriage return mechanism.

The invention may receive other embodiments than that herein specifically illustrated and described.

What is claimed is:

1. In automatic return mechanism for typewriter carriages, comprising a motor having a connection to a typewriter carriage, means for putting the motor in operation to effect return movement of the carriage, and means for automatically cutting off the operation of the motor on the return movement of the carriage; automatic cutting-off means comprising a toothed part off the carriage movable in synchronism therewith, a gear for driving said toothed part in synchronism with the carriage, means for disconnecting and reengaging said synchronously movable toothed part and driving gear to change the position of the synchronously movable part relative to the carriage for each different line-beginning position of the carriage to set the synchronously movable part to begin movement in synchronism with the carriage from an initial position which is the same for each line-beginning position, and a motor cut-off, said synchronously movable part being constructed and arranged to cooperate on its return movement with said motor cut-off, to actuate said motor cut-off to cut off the motor at a position of the synchronously movable part corresponding approximately to the chosen position of the carriage at which line-writing is to begin.

2. In automatic mechanism for typewriter carriages according to claim 1, said synchronously movable part being pivotally mounted, and said automatic cutting-off means further comprising gearing, including said driving gear, between said

synchronously movable part and the carriage, the construction and arrangement of the gearing being such that a full movement of the carriage imparts movement not exceeding 360° to said synchronously movable part.

3. In automatic return mechanism for typewriter carriages according to claim 1, said automatic cutting-off means further comprising means for automatically moving the synchronously movable part to its aforesaid initial position, for changes in the line-beginning position of the carriage.

4. In automatic return mechanism for typewriter carriages according to claim 1, wherein said synchronously movable part is a rotatable part, and said automatic cutting-off means further comprises an arm on which said rotatable synchronously movable part is mounted, said arm being movable to bring said synchronously movable part into and out of engagement with the gear which drives it, so that the synchronously movable part may be re-set to its aforesaid initial position to begin movement in synchronism with the carriage, for changes in the line-beginning position of the carriage.

5. In automatic return mechanism for typewriter carriages, comprising a motor having a connection to a typewriter carriage, means for starting the operation of the motor to effect return movement of the carriage, including a key-lever, and means for automatically cutting off the operation of the motor on the return movement of the carriage; automatic cutting-off means comprising a part off the carriage movable in synchronism therewith, reduction gearing for reducing the movement of the synchronously movable part in relation to the carriage movement, a motor switch and a motor clutch, a biased controller coacting with said switch and clutch, and a detent for holding said controller in switch-closing and clutch-closing position, said synchronously movable part being constructed and arranged to coact with said detent to actuate it to release the controller, and thereby open the switch and the clutch, to cut off the motor, at a position of the synchronously movable part corresponding approximately to a predetermined position of the carriage at which line-writing is to begin, said biased controller being so constructed and related to the key-lever of the motor starting means as to be movable by said key-lever to a position to be engaged by said detent, and means for changing the position of the synchronously movable part relative to the carriage for each different line-beginning position of the carriage to set the synchronously movable part to begin movement in synchronism with the carriage from an initial position which is the same for each line-beginning position.

6. In automatic return mechanism for typewriter carriages according to claim 5, wherein said controller is in the form of a bar, and said synchronously movable part, said detent, and said key-lever coacting therewith are arranged parallel to said bar.

7. In automatic return mechanism for typewriter carriages according to claim 1, said automatic cutting-off means further comprising means actuated by said synchronously movable part for advancing the cutting-off action of said motor cut-off, in relation to the distance which the carriage travels from line-beginning position, and hence the distance of the carriage return, so that the motor is cut off sooner when the

carriage return distance is long than at shorter distances.

8. In automatic return mechanism for typewriter carriages according to claim 1, said automatic cutting-off means further comprising means actuated by said synchronously movable part for advancing the cutting-off action of said motor cut-off, in relation to the distance which the carriage travels from line-beginning position and hence the distance of the carriage return, so that the motor is cut off sooner when the carriage return distance is long than at shorter distances, and means for holding said advancing means, during the return of the carriage, in the position to which it has been advanced.

9. In automatic return mechanism for typewriter carriages according to claim 1, said automatic cutting-off means further comprising means actuated by said synchronously movable part for advancing the cutting-off action of said motor cut-off in relation to the distance which the carriage travels from line-beginning position, said synchronously movable part having a cam thereon and said means for advancing the cutting-off action of said motor cut-off comprising a rocking part coacting with said cam.

10. In automatic return mechanism for typewriter carriages, comprising a motor having a connection to a typewriter carriage, means for putting the motor in operation to effect return movement of the carriage, and means for automatically cutting off the operation of the motor on the return movement of the carriage; automatic cutting-off means comprising a switch and a clutch, a controller operating to open and close said switch and clutch, a detent for holding

said controller in switch and clutch closing position during the return of the carriage by said motor, a part movable in synchronism with the carriage, coacting parts associated with said synchronously movable part and said detent for releasing said controller from said detent, a rocking part, a floating part connected to said rocking part and to said detent and having thereon said coacting part associated with the detent, a cam actuated by the carriage for turning said rocking part during the movement of said carriage from its line-beginning position and advancing said floating part and the coacting part thereon in the direction of the return movement of the coacting part associated with said synchronously movable part, means for clamping said rocking part, means on said controller for holding said clamping means out of action in the switch and clutch opening position of said controller corresponding to the period of advance of said floating part and for releasing said clamping means to act to hold said floating part in its position of advance in the switch and clutch closing position of said controller corresponding to the period of action of said motor to return said carriage, said cam and rocking part acting to increase the advance of the floating part and the coacting part thereon with increase of the carriage movement away from line-beginning position and said coacting parts on the return movement of the carriage consequently acting to release said controller from said detent and cut off said motor sooner when the carriage return distance is long than at shorter distances.

FREDERIC W. LE PORIN.
